Primary Examiner—Doris V. Coles*Assistant Examiner*—Cathron B. Matta*Attorney, Agent, or Firm*—Arnold White & Durkee[57] **CLAIM**

The ornamental design for a bottom of a foil container, as shown and described.

DESCRIPTION

FIG. 1 is an isometric view of a bottom of a foil container showing our new design;

FIG. 2 is a top plan view;

FIG. 3 is a bottom plan view;

FIG. 4 is a partial bottom plan view, shown at an enlarged scale;

FIG. 5 is a section, shown at a further enlarged scale taken generally along line 5—5 in FIG. 4;

FIG. 6 is a section, shown at a further enlarged scale taken generally along line 6—6 in FIG. 4;

FIG. 7 is a section, shown at a further enlarged scale taken generally along line 7—7 in FIG. 4; and,

FIG. 8 is a section, shown at a further enlarged scale taken generally along line 8—8 in FIG. 4.

Portions of the container are shown in broken lines for illustrative purposes only and form no part of the claimed design.
